UNITED STATES PATENT OFFICE.

JAMES PLEUKHARP AND WILLIAM K. LIGGETT, OF COLUMBUS, OHIO,
ASSIGNORS TO THE PLEUKHARP BARREL MACHINE COMPANY.

HOOP-MAKING MACHINE.

SPECIFICATION forming part of Letters Patent No. 501,730, dated July 18, 1893.

Application filed September 26, 1892. Serial No. 446,937. (No model.)

To all whom it may concern:

Be it known that we, JAMES PLEUKHARP and WILLIAM K. LIGGETT, citizens of the United States, residing at Columbus, in the county of 5 Franklin and State of Ohio, have invented certain new and useful Improvements in Hoop Making Machines; and we do hereby declare the following to be a full, clear, and exact description of the invention, such as will enable 10 others skilled in the art to which it appertains to make and use the same.

This invention relates to machines for making hoops which are formed from hoop iron that is cut the required length, bent in circular form, and having the ends overlap and secured together by rivets.

The purpose of the present invention is to devise a machine for punching and riveting the overlapping ends of the hoop iron automatically and in which the jaws and die plates carrying the punching, riveting, and wire feeding mechanism will be relatively fixed as regards any longitudinal movement thereof, and which will tilt on their pivotal support 25 only to open and close said jaws on the overlapping ends of the hoop iron.

A further purpose of the invention is to provide simple and efficient mechanism for moving the former around which the hoop 30 iron is bent so as to carry the overlapping ends of the hoop iron between the die plates of the jaws at the proper time and in proper position to be operated upon by the punching mechanism, receive the rivets, and upset the 35 ends of the rivets, thereby completing the operation of riveting the overlapping ends of the hoop iron.

A still further purpose of the invention is to improve this class of machinery and provide 40 a machine which will be comparatively simple in construction, efficient and perform the work in a rapid and satisfactory manner, and which will be durable, easily manipulated, and in which the parts are readily accessible 45 for purposes of repair and cleaning.

The improvement consists of the combination with a pair of jaws carrying the punching, wire feeding and riveting devices, of a former to receive the hoop iron forming the hoop, 50 and mechanism for moving said former to carry the overlapping ends of the hoop iron

between said jaws, whereby said overlapping ends are successively punched, receive the rivets, and have the ends of the rivets upset.

The improvement also consists in the combination with the jaws carrying the punching, riveting, and rivet feeding mechanism, of a slide to cut the rivets from a wire and clamp said rivets until thrust into the openings in the overlapping ends of the hoop iron. 55

The improvement further consists of the special instrumentalities for operating the former, separating the parts or sections composing said former and returning the same to a normal position after being actuated; the 60 provisions for adjusting the wire feeding rollers to cause them to grip the wires with a greater or less degree of tension; the lubricating attachment for oiling the punching device; the receptacle for receiving the cuttings; 65 and the instrumentalities for starting and stopping the machine and for actuating the jaws, and the wire feeding mechanism which will be hereinafter more fully described and claimed, and which are shown in the accompanying drawings, in which— 70

Figure 1 is a side elevation of a hoop forming machine embodying our invention. Fig. 2 is a front view of the said machine. Fig. 3 is a view from the rear side of the machine 80 having a portion of the large gear wheel broken away to show the relative disposition of the rim, the pawl for locking the drive pulley to the drive shaft, and the trip which has one end in engagement with said rim and 85 the other end constructed to engage with said pawl to release the drive pulley to permit it to revolve freely on the drive shaft, and shows the drive pulley and the inner portion of the sleeve which carries said pawl in section. Fig. 4 is a vertical section of the machine looking to the right, showing the jaws and the former in central longitudinal section. Fig. 5 is a detail view of the wire feeding mechanism on a larger scale, showing a 90 portion of the lever which carries the feed pawl in section to illustrate the relative disposition therewith of said feed pawl and its actuating spring. Fig. 6 is a detail plan view of the wire feeding mechanism, showing the 95 devices for relatively adjusting the feed roller. Fig. 7 is a detached view of the drive pulley 100

looking at that side which is provided with the shoulders with which the pawl engages to lock the drive pulley and drive wheel together.

The frame of the machine which is preferably of metal, is composed of two similar side pieces A which are connected and braced by suitable cross bars. The shaft B journaled near its ends in bearings provided on the side pieces A, has a pulley C mounted and adapted to rotate freely thereon and is provided at one end with a pinion D the sleeve d of which extends to and abuts against the hub of the pulley C. This pinion D and sleeve d are keyed on the said shaft B so as to revolve therewith. A lateral extension d' projecting from the sleeve d is recessed to receive an elbow shaped pawl E which is pivotally connected with the said extension d' at the elbow. The horizontal member e of the pawl E projects away from the pulley C and the vertical member e' occupies a pendent position and is adapted to be pressed toward the pulley C by a spring d' which is fitted in a recess in the said extension d'. The side of the pulley C facing the pawl E, has two cam faces C' on the inner periphery of the band, and two shoulders C² at points diametrically opposite each other. Obviously, when the member e' is projected within the plane of the pulley C it will be engaged by one or the other of the shoulders C² and lock the pulley C and shaft B so that they will revolve together. An elbow shaped trip F pivotally supported at the elbow has its horizontal arm f approximately parallel with shaft B and its vertical arm f' in a plane parallel with the pulley C. The rear edge of the arm f' is provided with a cam f² which is eccentric to and extends about one-third way around the shaft B and is disposed so as to engage with the horizontal member e and disengage the vertical member e' from the pulley C. The lower end of the arm f' is attached to a hand lever X which is pivoted to the frame of the machine, and extends forward so as to be within convenient reach of the operator. By means of this lever the trip F is made to turn on its pivot, the lower end of the vertical arm f' swinging outward releasing the pawl E. See the dotted lines in Fig. 3. The trip F may be returned to a normal position by gravity, but to insure its quick and positive action a spring f⁴ is provided and located between the horizontal arm f and the frame. The shaft K parallel with the shaft B and journaled on the said side pieces A, is provided on one end by a gear wheel L which is constructed to mesh with the pinion D and which has a rim l on its inner side to extend within the path of the free end of the arm f. This rim has a depressed portion l' which receives the end of the said arm f when the trip is in a normal position, i. e. when the machine is out of gear. During the time that the machine is in gear the arm f travels upon the rim l and holds the cam f² out of the path of the member e of pawl E. On this shaft K

is mounted a series of cams 1, 2, 3, 4, 5, 6, for actuating the jaws which carry the punching and riveting mechanism and for operating the wire feeding devices.

The jaws M and N are mounted on a cross bar O and have anti-friction rollers m and n at their rear ends to travel on the respective cams 2 and 6, and 3 and 5. These anti-friction rollers are mounted in boxes which are let into the said jaws and which are adjusted by means of set screws m'. The rear end of the lower jaw N is held against the cams 3 and 5 by means of a spring P². The weight of the rear portion of the jaw M is sufficient to hold it in engagement with the cams 2 and 6.

The wire feeding mechanism composed of grooved rollers Q and R, is carried by the lower jaw N. These rollers are suitably mounted in the said jaw and have cog gearing q intermediate of their ends by means of which the said rollers are positively rotated together. The journal of one of the rollers is extended and a ratchet wheel S secured thereto and a lever T mounted so as to turn loosely thereon. The lever T is provided at its lower end with a pawl t fitting into a socket provided therein and adapted to be engaged by a spring s by which it is kept in contact with the ratchet wheel S. The rod T' depending from one end of the lever T connects with the front end of a lever T² the rear end of which is constructed to engage with the cam 1 and be operated thereby. This lever T² is pivotally supported intermediate of its ends on a side A of the frame of the machine, and is provided at its inner end with an anti-friction roller to travel on the cam 1, and is held against said cam by a spring t'. The grooves in the rollers Q and R, are roughened to engage the wire and the front roller Q is journaled in sliding boxes q' adjusted by the set screws q² by which the grip on the wire may be altered or adjusted.

The formers U and V, each being semi-circular in outline, are located on the front side of the machine and are placed to form a complete circle when together. These formers are mounted on vertical guide rods W and are connected together by toggle levers u and u', the lever u being connected with the treadle by the rod u². The lower former V is adjustably connected with a cross head 7 which is mounted on the guide rods W and to which the toggle levers u are connected. The former V is vertically adjusted with reference to the cross head 7 by means of the set screws u³ which pass through a rear extension of the former V and screw into the said cross head 7. Obviously, by adjusting the former V the machine can be adapted to different sizes of hoop. The springs w mounted on the lower portion of the guide rod W and supported on collars w' serve to return the former V to a normal position after being actuated. Jaws 8 are provided above the upper former U to act in opposition thereto to grip the overlapping ends of the hoop iron. This upper

former U is cut away to permit the free working of the lower jaw N and admit of the wire feeding mechanism being so disposed that the wire receiving space between the rollers Q and 5 R will come directly below the wire opening in the said jaw N as shown most clearly in Fig. 4. The vertical rods W are hinged at w^2 at their lower ends to the frame of the machine, allowing an in and out or backward and forward movement or oscillation of the hoop forming and carrying mechanism. The vertical guide rods W are also provided with an arm Y extending backward and upward, and furnished with an extension y adapted to engage the grooved cam Z of the wheel L. This grooved cam Z is constructed with three concentric arcs of different radii, by the engagement with which of the extension y on the arm Y the in and out or backward and forward movement of the hoop forming and carrying device is secured.

Located between and supported by the jaws M and N are the die plates P and P'. The die plate P is provided with punches 9, the 25 openings 10, (of the width of the wire and elongated in a plane at right angles to the front of the machine or the shaft K,) and the depressions 11. The die plate P' is provided with openings 12 directly opposite the punches 9, to receive the cuttings, openings 13 opposite the elongated openings 10 to receive the wire 14, and depressions 15, corresponding with the depressions 11, in the plate P to give the proper shape to the heads of the rivets.

35 The slide H moving in bearings in the jaw N, is provided at its forward end with a hardened steel plate or shearing tool h and at its farther end with an adjustable plate h' adapted to engage the cam 4, by which the said 40 slide is actuated. The plate h' is kept in contact with the cam 4 by means of the spring h². A receptacle 16 is provided in the lower jaw N to receive the cuttings from the punching tools. An oiler 17 is also provided in the 45 upper jaw M, with an opening to convey the oil to the punches and keep them constantly lubricated.

The treadle J is held and returned to a 50 normal position after being operated by the spring J' which is interposed between a lower cross bar of the frame and a depending projection of the said treadle. The set screws j are provided to regulate the tension of this spring as shown most clearly in Fig. 4.

55 The hoop iron, previously cut to approximately the required length, is placed around the formers and its ends lapped. The overlapping ends being placed between the former U and the jaws 8, the operator presses down on 60 the treadle J which through rod u² and the toggle levers u and u' separates the formers and at the same time lifts them sufficiently to clamp the overlapping ends of the hoop between the upper former and the jaws. The springs 65 w carrying the weight of the formers act as a yielding resistance. When the treadle is depressed the upper former will be elevated

until the hoop is clamped between it and the jaws 8. A continued downward pressure on the treadle forces the lower former down 70 against the tension of the springs w. By this construction provision is had to permit the overlapping ends of the hoop to slip during the separation of the formers U and V and yet hold them with sufficient tension during 75 the operation of punching and riveting. The hoop thus formed the size desired, and securely held in position in the machine is ready to be operated upon by the punching and riveting mechanism. The operator now moves 80 the lever X releasing the pawl E and permitting the same to lock the pulley C and the shaft B together, thereby starting the machine. The arm f' is held out of the path of the pawl E by the arm f riding on the rim l. The lower jaw then comes up first with the die against the work and immediately after the upper jaw comes down with the punches making the holes in the hoop. Then both jaws open simultaneously at which time the wire 14 is fed through 90 the suitable holes in the lower jaw the required length for a rivet. The hoop holding mechanism then moves backward under the action of the arm Y and cam Z. At the same time, the slide H moves forward under the 95 action of the cam 4 shearing off the wire and clamping it securely between a shoulder p on the die P' and the end of the slide H directly beneath the holes in the hoop. The jaws again coming together under the action of the 100 operating cams, (2, 3, 5, 6) force the rivets up through the holes in the hoop, where they are retained by friction. The jaws again re-open leaving the rivets in the hoop, the slide H moving backward releasing them from die P'. 105 The hoop holding mechanism now moves forward under the action of arm Y, and cam Z until the rivets stand directly opposite the recesses 11 and 15 in the die plates. The jaws then close bringing the recesses 11 and 15 of 110 the die plates P and P', respectively, upon the ends of the rivets making a round head. The jaws again re-open and the hoop holding mechanism returns to point of starting under the action of arm Y and cam Z. The arm f 115 of trip F drops into recess I', the machine is automatically stopped and the completed hoop is removed.

This machine is designed as an improvement on that for which we filed application 120 for patent of the United States April 12, 1892, Serial No. 428,865. In said application the former about which the hoop iron is shaped is relatively fixed as regards the jaws, the die plates being movable to perform the operation of punching, and riveting the overlapping ends of the hoop iron. The present invention differs from that forming the basis of the aforesaid application, Serial No. 428,865, 125 in the former about which the hoop iron is shaped and the mechanism for actuating the same, whereby the said former is moved to carry the overlapping ends of the hoop iron between the jaws to be successively oper- 130

ated upon by the punching, and the riveting mechanism as more particularly set forth hereinbefore and pointed out in the annexed claims. The particular construction of the former, the punching and the riveting mechanism, and the instrumentalities for separating the parts of the former and starting and stopping the machine, and the wire feeding mechanism are substantially the same as that set forth in the application hereinbefore mentioned, Serial No. 428,865, and is claimed therein.

Having thus described our invention, what we claim, and desire to secure by Letters Patent, is—

- 15 1. In a hoop forming machine the combination with jaws provided with the punching and riveting mechanism, of a former to receive the hoop iron, and mechanism for moving said former to carry the overlapping ends of the hoop iron between the jaws to be successively operated upon by the punching, and the riveting mechanism, substantially as set forth.
- 25 2. In a hoop forming machine the combination with jaws carrying the punching, riveting, and rivet feeding mechanism, of a former adapted to receive the hoop iron, and mechanism for moving said former to carry the overlapping ends of the hoop iron between said jaws to be successively punched, receive the rivets, and have the ends of the rivets upset, substantially as set forth.
- 35 3. In a hoop forming machine the combination with the jaws carrying the punching and riveting mechanism and a wheel as L having a cam Z having portions at different radii, of a former having an arm projected therefrom, and having a portion of said arm engaging with the cam Z whereby said former is moved backward and forward to carry the hoop iron between said jaws to be successively operated upon by the punching and riveting mechanism, substantially as set forth.
- 45 4. In a hoop forming machine the combination with the jaws carrying the punching and riveting mechanism and a wheel L having a grooved cam Z having portions at different radii, of a pivoted former to receive the hoop iron having an arm projected therefrom and provided with a portion to engage with said grooved cam, whereby said former is rocked on its pivotal support, substantially as described for the purpose set forth.
- 55 5. In a hoop forming machine the combination with the jaws carrying the punching and riveting mechanism, and the wire feeding mechanism, of a slide constructed to sever portions from the wire to form the rivet, and mechanism for actuating the said slide and the wire feeding mechanism, substantially as set forth.
- 65 6. In a hoop forming machine the combination with the jaw M having elongated opening 10, and the jaw N having an opening to permit of the passage of the rivet forming wire, and having shoulder p, of a slide con-

structed to sever portions from said wire to form the rivet and clamp said rivet between said shoulder p and the end of the slide, substantially as set forth.

70 7. In a hoop forming machine the combination with the jaws provided with the punching and riveting mechanism, and an actuating cam, of a slide for cutting the rivets provided with an adjustable end piece to ride upon said cam, substantially as set forth.

75 8. In a hoop forming machine the combination with the jaws carrying the punching and riveting mechanism a shaft provided with cams for actuating said jaws and the wire feeding mechanism, and a wheel L mounted on said shaft and having a rim l which is provided with a depressed portion l', of a drive shaft, a drive pulley loosely mounted on said drive shaft, a pawl E carried by said drive shaft and adapted to engage with said drive pulley, a trip adapted to have one end to travel on the rim l and having its other portion provided with a cam f², and a lever under the control of the operator to move said trip and project the cam portion f² within the path of a portion of the pawl E, substantially as and for the purpose set forth.

90 9. In a hoop forming machine the combination with the jaws carrying the punching and riveting mechanism, feed rollers Q and R, and a shaft provided with a series of independent cams for actuating said jaws and the feed rollers, of a ratchet wheel S on the journal of one of said rollers, lever T loosely mounted on the journal and provided in one end with a socket, a spring actuated pawl located in the said socket to engage with said ratchet wheel, lever T² pivoted between its ends, one end being constructed to engage with one of the said cams, and having the other end connected with the lever T, and a spring t' for maintaining the free end of the lever T² in engagement with the actuating cam, substantially as set forth.

95 10. In a hoop forming machine the combination with the jaws carrying the punching and riveting mechanism, of wire feeding rollers located in one of said jaws, adjustable bearings for one of said rollers, and set screws for adjusting said bearings to vary the distance between said rollers, substantially as set forth.

110 11. In a hoop forming machine, the combination of the jaws M and N carrying the punching mechanism, the jaw N having receptacle 16 projected forwardly therefrom and communicating with the opening through which the cuttings escape, to receive the said cuttings and the lubricant, and a lubricator to automatically supply oil to the punching mechanism, substantially as described.

In testimony whereof we affix our signatures in presence of two witnesses.
